(57) **CLAIM**

The ornamental design for a gaming machine, as shown and described.

DESCRIPTION

FIG. 1 is a perspective view from above of a gaming machine showing the design.

FIG. 2 is a front view of the gaming machine shown in FIG. 1.

FIG. 3 is a back view of the gaming machine shown in FIG. 1.

FIG. 4 is a right side view of the gaming machine shown in FIG. 1.

FIG. 5 is a left side view of the gaming machine shown in FIG. 1.

FIG. 6 is a top view of the gaming machine shown in FIG. 1; and,

FIG. 7 is a bottom view of the gaming machine shown in FIG. 1.

The evenly spaced broken lines shown in the drawings depict environmental structure and form no part of the claimed design.
